FLOAT CONTROL

Otto Thiel, Detroit, Mich.

Application July 29, 1943, Serial No. 496,603

1 Claim. (Cl. 137—69)

This application relates to float controls and more particularly to float controls responsive to liquid level for operating a snap action device, such as a valve for gas-charged-liquid devices, such as carbonators.

In a prior application, Serial No. 446,949, filed June 13, 1942, there is shown a valve needle raised and lowered with snap action by a float control including two hollow balls slidably mounted on an operating rod connected to and raised and lowered by the balls, and also connected to the needle by a snap action mechanism. In this application, for raising and lowering rod 36 and valve needle 31, I have provided a float control comprising two cups, the lower one of which is fastened to the rod 36, and the upper one of which, inverted, is slidably mounted on rod 36.

The float control of my invention is shown in the appended drawing.

In this drawing,

Fig. 1 shows a device containing my float control.

Fig. 2 diagrammatically illustrates the connection between the operating rod 36 and the valve needle 31, established through a snap action mechanism.

Fig. 3 is a section view showing the float control in greater detail.

Fig. 4 is a section on line 4—4 of Fig. 3.

The drawing shows a tank 10 having its open upper end closed by a base 11 supporting a water and gas inlet tube 12 connected to an inlet pipe 14 and a charged water outlet tube 15 connected to an outlet pipe 16. The base has an opening 19 into which threads a venting tube 20 having a vent hole 22. Opening 19 is adapted to be closed by a needle valve 31, and forms a valved gas vent for the tank.

Valve needle 31 is operated to open or close, with a snap action, on low or high level of the water in the tank, by a float controlled snap action mechanism consisting of an operating rod 36 pivotally connected at 37 to a link 38 pivoted on a stationary pivot 39 and connected by a tension spring 40 to the end 41 of a link 42 pivoted on a stationary pivot 43 and connected at 44 to the needle valve 31. As rod 36 drops or rises, the needle 31 will drop or rise to open or close the vent opening 19.

For controlling the travel of the rod 36, there is slidably mounted thereon an upper inverted annular cup 47 and there is fastened thereto a lower cup 48. The rod has an abutment nut 49 threaded on it above cup 47, and the latter has a supporting strap 50 resting on plate 51

soldered to tubes 12 and 15. A strap 50 is provided with a hole 52 through which freely passes rod 36.

Operation

5 The lower cup 48 is always full of water, and therefore has added weight unless it is submerged. When not submerged, its weight will pull rod 36 down and lower needle 31, permitting gas to escape from tank 10, whereupon water will enter through pipes 14 and 12. The rising water level raises upper cup 47 against stop 49 to raise rod 36 and needle 31, to close opening 19 with a snap action. As charged water is drawn from the tank, the level drops and cup 47 will no longer be buoyant and will drop, without however pulling down on rod 36 or needle 31. As the level continues to drop, below cup 48, the latter will drop and pull down rod 36 and needle 31.

20 Strap 50 supports cup 47 on plate 51 when the cup is not supported by the level of the water.

The float control herein shown is better than the hollow ball construction of my prior application Serial No. 446,949 because it is non-collapsible. The hollow balls of my prior construction tend to collapse under high pressure. The cups herein shown do not collapse, despite their being made of thin sheet metal for lightness.

25 Now having described the improvements herein disclosed, reference should be had to the claim which follows.

I claim:

30 A float control for operating a snap action device comprising an operating rod connected to said device and arranged to be reciprocated vertically for different operations of said device, a chamber for receiving a liquid, an open top, 40 closed bottom, cup fastened to the lower end of the rod within the chamber, an open bottom, closed top, float above the cup and slidably mounted on the rod within the chamber, an abutment on said rod above the float arranged 45 to be engaged by the float when the liquid level rises so that rise of the float will lift the rod, the float having means free of the rod for limiting its downward movement and said float being completely free of the snap action device except 50 for said engagement with the abutment on the rod, whereby said float on rising may lift the rod and operate the device but on falling will not lower the rod nor operate the device and said cup will fall and operate said device when the 55 water level falls below said cup.

OTTO THIEL.
